UNITED STATES PATENT OFFICE.

WALTER F. KOKEN, OF ST. LOUIS, MISSOURI, ASSIGNOR TO KOKEN BARBERS' SUPPLY COMPANY, OF ST. LOUIS, MISSOURI, A CORPORATION OF MISSOURI.

DESIGN FOR A CHILD'S HAIR-CUTTING CHAIR.

48,943.

Specification for Design.

Patented Apr. 25, 1916.

Application filed December 11, 1915. Serial No. 66,390. Term of patent 14 years.

To all whom it may concern:

Be it known that I, WALTER F. KOKEN, a citizen of the United States, residing at St. Louis, Missouri, have invented a certain new, original, and ornamental Design for a Child's Hair-Cutting Chair, of which the following is a specification, reference being had to the accompanying drawing, forming part thereof.

The figure of the drawing is a perspective view of my design for a child's hair cutting chair.

I claim:

The design for a child's hair cutting chair, as shown.

WALTER F. KOKEN.
